CONNECTER FOR SPARK PLUG TERMINALS

Otto E. Szekely, Holland, Mich.

Application December 1, 1930, Serial No. 499,235

5 Claims. (Cl. 173—269)

This invention relates to connectors of the type used with the terminals of spark plugs of the character employed in internal combustion engines and particularly, though not necessarily, to spark plugs for aircraft engines. The blast from the propeller of an aeroplane usually passes directly over the motor driving the propeller and as this blast is of appreciable force it is not uncommon that the ignition wires are disconnected thereby from the spark plugs of the engine. Even in engines wherein the ignition wires are covered and protected from the blast this displacement sometimes occurs, due to vibration, and obviously if one ignition wire is disconnected additional vibration will result, because of the inoperative cylinder, and this additional vibration may displace other ignition wires. It has frequently been the custom, to obviate the foregoing condition, to wire, or otherwise fixedly secure, the connectors to the terminal of the spark plugs to prevent displacement and the disadvantage of this will be readily apparent, and sometimes negligent mechanics fail to take this precaution with the result that the connectors are displaced from the terminals of the spark plugs when the engine is in use.

It is therefore the salient object of my invention to provide a novel connector for the terminal of spark plugs which will be so constructed that a positive connection may be made with the plug in a manner which will eliminate the likelihood of displacement and an ancillary object is to provide a connector which may be easily disconnected manually when so desired. A further object is to provide a connector which will not be weakened even though it is repetitiously connected and disconnected and this resides in the provision of sufficient innate resiliency to overcome any likelihood of fatigue in the metal.

A selected embodiment of my invention is illustrated in the accompanying drawing and therein

Fig. 1 is a top plan view of my improved connector in installed position;

Fig. 2 is a sectional view taken substantially on the line 2—2 on Fig. 1;

Fig. 3 is a sectional view taken substantially on the line 3—3 on Fig. 1; and

Fig. 4 is a bottom plan view of my improved connector.

In the selected embodiment of my invention illustrated in the accompanying drawing 5 indicates the body of my novel connector which is formed from a strip of sheet metal, suitably shaped, and having at one end thereof a bifurcation 6 terminating in a centrally extending slot

7, disposed in the stem portion 8, the bifurcation 6 being formed, as by rounding, as indicated at 9, to embrace the reduced portion 10 on the terminal 11 of the spark plug generally indicated by 12. The strip 5 includes an enlarged portion 13, outwardly of the stem portion 8. Disposed on one face of the strip 5 is a resilient strip 14, one end of which is secured to the portion 13 by the rivet 15 or other suitable securing device. At the end of the strip 14, opposite the end through which the rivet 15 is passed, there is an enlarged portion 16 having an opening 17 therein, the forward end of which is of substantially circular contour and the rear end of which is in the form of a slot 18. The opening 17 is aligned with the bifurcation 6. At the forward end of the strip 14 there is a lip 19, the utility of which will be made apparent presently. Extending from the strip 14 on opposite sides of the opening 17, in diametrical relation, are two clamping sections 20, 20 which, at a point outwardly of the strip 14, are rolled to provide rounded portions 21, 21 and tail portions 22, 22 extend from these rounded portions over the lower face of the strip 5, as best illustrated in Figs. 3 and 4. The tail portions 22, 22 and the rounded portions 21, 21 cooperate to yieldingly hold the sections 20, 20 in engagement with the upper surface of the portion of the strip 5 adjacent the bifurcation 6. The end of the strip 5, outwardly of the portion 13, is bent at right angles to the extent of the strip to provide a portion 24 in which an opening 25 is provided through which the neck 26 of the conductor receiving socket 27 is extended. One end of the socket engages one face of the portion 24 and the end of the neck 26 is flared outwardly, as indicated at 28, to connect the socket to the portion 24 and the strip 5. A sleeve 29 of insulating material is disposed about the body portion of the socket 27 and extends beyond the end thereof to conceal and protect the electric conductor connected in said socket as by soldering or in any other approved manner. On the terminal 11, outwardly of the reduced portion 10, is a collar 23.

To install my improved connector, the end of the section 5 adjacent the bifurcation 6 is disposed with the bifurcation in alignment with the reduced portion 10 and by applying pressure the sections of the strip 5 on each side of the bifurcation will spring outwardly, this being aided by the slot 7, and thus the periphery of the reduced portion 10 may be embraced by the arcuated portions 9. During the time the strip 5 is being forced on to the reduced portion 10 the enlarged portion 16 will be cammed upwardly, as illus-

trated in dotted lines in Fig. 2, until the opening 17 therein is alined with the collar 23 so that the collar 23 may be forced therethrough and a portion of the section 16, at the edge of the opening 17 adjacent the lip 19, will engage the reduced portion 10 below the collar 23 and this portion will cooperate with the rounded sections 9 to securely attach the connector to the terminal 11. To insure retention of the member 5 about the reduced portion 10 the ends of the tail portions 22, 22 are disposed to extend into said reduced portion, as illustrated in Fig. 3. When it is desired to disconnect the connector, pressure is applied on the underside of the lip 19 and by reason of the innate resiliency of the strip 14 this strip may be sprung to the dotted line position of Fig. 2 after which the strip 5 may be withdrawn from engagement with the reduced portion 10.

By reason of the fact that the reduced portion 10 will be embraced by the sections of the strip 5 on the opposite sides of the bifurcation 6 and by the portion of the strip 16 at the edge of the opening 17, in opposition to the rounded portions 9, and as the clamping sections 20, 20 will serve to hold the strip 16 on the upper surface of the strip 5, accidental displacement will be prevented, for the connector cannot be disconnected save by applying pressure to the lip 19 to spring the strip 16, as above set forth.

While I have illustrated and described a selected embodiment of my invention, it is to be understood that this is capable of variation and modification and I therefore do not wish to be limited to the precise details set forth but desire 35 to avail myself of variations and modifications within the purview of the following claims.

I claim:

1. In a connector of the class described, a strip having a terminal embracing bifurcation extending thereto from one end thereof, a clamping strip having one end thereof secured to the end of said first named strip opposite the bifurcation, said clamping strip having a terminal embracing opening therein alined with the bifurcation, and yieldable means unitary with the clamping strip for holding said clamping strip in engagement with one face of the first named strip and including portions embodying resilient sections and limb portions engaging the opposite face of said first named strip.

2. A connector of the class described including a body strip having a bifurcation at one end thereof and a slot extending inwardly from said bifurcation and having formed portions at the inner end of said bifurcation, a yieldable clamping strip on one face of said body strip, means connecting one end of said clamping strip to said body strip, said clamping strip having an opening therein alined with the formed portions of said bifurcation, clamping sections extending from the edges of said clamping strip in alinement with the opening therein, said clamping strips being rolled to provide rounded portions and including tail portions extending from said rounded portions over the other face of said body where-

by said clamping sections yieldingly hold said clamping strip on said body strip, and a lip on said clamping strip projecting beyond the end of said body strip providing means adapted to be grasped to facilitate bending of said clamping strip from engagement with said body strip against the action of said clamping sections.

3. In a spark plug which has a terminal including a reduced portion and a collar arranged above said reduced portion, the combination of a connector including a body strip having a bifurcation therein adapted to embrace the reduced portion of said terminal, a yieldable clamping strip, means connecting corresponding ends of said body strip and clamping strip whereby said clamping strip is positioned on one face of said body strip, said clamping strip having an opening therein adapted to embrace said collar, and yieldable means unitary with said clamping strip and including portions engaging said body strip and adapted to hold said clamping strip in engagement with said body strip with the opening in said clamping strip embracing said collar on said terminal.

4. In a spark plug which has a terminal including a reduced portion and a collar arranged above said reduced portion, the combination of a connector including a body strip having a bifurcation therein adapted to embrace the reduced portion of said terminal, a yieldable clamping strip, means connecting corresponding ends of said body strip and said clamping strip whereby said clamping strip is positioned on one face of said body strip, said clamping strip having an opening therein adapted to embrace said collar, and yieldable means unitary with said clamping strip and including limb portions extending about the edges of said body strip across the face thereof opposite the face on which said clamping strip is positioned, the ends of said limb portions extending into the reduced portion of said terminal to retain said clamping strip in engagement with said body strip to hold said connector in engagement with said terminal when said reduced portion is embraced by said bifurcation and said collar is embraced by said opening.

5. In a spark plug which has a terminal including a reduced portion and a collar arranged above said reduced portion, the combination of a connector including a body strip having a bifurcation therein adapted to embrace the reduced portion of said terminal, a yieldable clamping strip, means connecting corresponding ends of said body strip and said clamping strip whereby said clamping strip is retained in position on one face of said body strip, said clamping strip having an opening therein adapted to embrace said collar, and clamping sections unitary with said clamping strip and including limb portions extending across the other face of said body strip into said reduced portion to urge said clamping strip toward said body strip with the opening therein embracing said collar to thereby retain said connector on said terminal.
